UNITED STATES PATENT OFFICE.

JAMES K. DALTON, OF WAVERLY, OHIO.

BONE-SAW, &c.

1,097,171.

Specification of Letters Patent. Patented May 19, 1914.

Application filed October 31, 1913. Serial No. 798,506.

To all whom it may concern:

Be it known that I, JAMES K. DALTON, a citizen of the United States, residing at Waverly, in the county of Pike and State of Ohio, have invented certain new and useful Improvements in Bone-Saws, &c.; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in combined meat knife, bone saw and steak pounder and comprises a simple and efficient device of this nature having various details of construction and combinations and arrangements of parts which will be hereinafter fully described, shown in the accompanying drawings and then specifically defined in the appended claim.

I illustrate my invention in the accompanying drawings, in which:—

Figure 1 is a central sectional view through a knife and saw made in accordance with my invention. Fig. 2 is a part showing the handle removed, and Fig. 3 is a cross sectional view on line 3—3 of Fig. 1.

Reference now being had to the details of the drawings by letter, A designates a knife blade having a shank portion H which is tapering and upon one edge is recessed as at C. A saw, designated by letter D, is pivotally connected to the pin E at one end and its other end fastened to a pin F which is carried by the upward lug of the member H, which latter is held against the rear edge of the shank portion of the knife and tapers toward its inner end and is threaded as at K. A handle, designated by letter O, has a tapering recess therein for the reception of the shank portions B and H and a nut, 45 designated by letter R, is adapted to engage

the threaded end K and seat in an enlarged chambered portion of the recess of the handle, a suitable lock T being provided upon the threaded part K. Said nut has a circumferential flange R' about the same which 50 is adapted to engage over the end of the handle and its outer end T² is serrated, forming a suitable meat tendering device, while a ferrule S is fitted over the forward end of the handle.

By the provision of a combined knife, saw and meat tendering device embodying the features shown, it will be noted that a simple and efficient device is afforded so arranged that the saw may be drawn taut and held by the turning of the nut upon the end of the handle, both the knife blade and the member to which the saw is pivoted being securely held within the handle.

What I claim to be new is:—
A bone saw, etc., comprising a bar with a shoulder which is recessed, a saw having apertures in the ends thereof, a pin passing through the wall of said recess and to which one end of the saw is pivoted, a movable member mounted upon the edge of said bar, tapering upon one edge and having a lug projecting therefrom, a pin carried by said lug and to which the other end of the saw has pivotal connection, said member having 75 a threaded end, the bar adjacent to said member being contracted and tapering, a handle fitted over said member and tapering end of the bar, and a nut having a socket portion which is threaded for engagement with 80 the threaded end of said member and the end of the handle chambered for the reception of said nut, as set forth.

In testimony whereof I hereunto affix my signature in presence of two witnesses.

JAMES K. DALTON.
